UNITED STATES PATENT OFFICE.

GEORGE D. MERRILL, OF EAST ORANGE, NEW JERSEY.

DESIGN FOR A SPOON OR SIMILAR ARTICLE.

SPECIFICATION forming part of Design No. 33,414, dated October 23, 1900.

Application filed August 10, 1900. Serial No. 26,530. Term of patent 3½ years.

To all whom it may concern:

Be it known that I, GEORGE D. MERRILL, a citizen of the United States, residing at East Orange, county of Essex, State of New Jersey, have invented and produced a certain new and useful Design for a Spoon or Similar Article; and I do hereby declare the following to be a full, clear, and exact description of the invention, such as will enable others skilled in the art to which it appertains to make and use the same.

This invention relates to a new and useful design for a spoon or similar article.

The object of my invention is to provide a spoon with certain peculiar distinguishing features of design, which are so combined as to impart a strikingly novel and artistic effect to the article as an entirety.

The accompanying drawing shows the article of manufacture in elevation, dotted lines indicating a spoon-bowl and fork-tines.

The straight stem *a* has the spoon-bowl at one end and a laterally-projecting head *d* at

its opposite outer end. A short outer portion *d'* of said stem adjacent to said head *d* ²⁵ tapers longitudinally of the stem and toward the inner end thereof, carrying the bowl, and is formed with a continuous closely spirally ribbed surface. A short inner portion *b* of said stem tapers or is gradually reduced from ³⁰ the spoon-bowl longitudinally of the stem, toward the outer end thereof, and is encircled by a spiral groove *c*, extending longitudinally throughout the length of said tapered portion *b*.

Having thus fully described my invention, what I claim as new, and desire to secure by Letters Patent of the United States, is—

The design for a spoon, substantially as described and shown.

In testimony whereof I affix my signature in presence of two witnesses.

GEORGE D. MERRILL.

Witnesses:

J. M. MERRILL,
ALBERT HALLOWELL.
